(57) **CLAIM**

The ornamental design for a microphone boom for a communications headset, as shown and described.

DESCRIPTION

FIG. 1 is an upper left front perspective view of a microphone boom for a communications headset showing our new design;

FIG. 2 is a front elevation view thereof;

FIG. 3 is a rear elevation view thereof;

FIG. 4 is a bottom plan view thereof;

FIG. 5 is a top plan view thereof;

FIG. 6 is a right side elevation view thereof; and,

FIG. 7 is a left side elevation view thereof.

The ornamental design that is claimed is shown in solid lines in the drawings. The broken line outline of a headset earpiece is shown in the drawings for environmental purposes only, and forms no part of the claimed design.
